AUTOMOBILE PARKING AID

Richard W. Whitehill, Cleveland, Ohio

Application November 19, 1953, Serial No. 27,677

Term of patent 14 years

(Cl. D14—6)

FIG. 1

FIG. 2

Fig. 1 is a top plan view of an automobile parking aid, showing my new design;

Fig. 2 is a side elevational view thereof.

I claim:

The ornamental design for an automobile parking aid, as shown.
